HOUSING FOR A PORTABLE HAIR DRYER

Ivar Jepson and Robert O. Ernest, both of Oak Park, Ill.,
assignors to Sunbeam Corporation, Chicago, Ill., a cor-
poration of Illinois

Filed Dec. 11, 1961, Ser. No. 67,865

Term of patent 14 years

(Cl. D86—10)

FIG. 3.

FIG. 4.

FIG. 1 is a perspective view of a housing for a portable hair dryer showing our new design;

FIG. 2 is an enlarged scale front elevational view thereof, the broken line illustration of the lid and handle having been omitted for convenience of illustration;

FIG. 3 is an enlarged scale sectional view taken along the section line 3—3 of FIG. 1; and

FIG. 4 is an enlarged scale front elevational view taken along the section line 4—4 of FIG. 2.

The dominant features of our design reside in the portions shown in full lines.

We claim:

The ornamental design for a housing for a portable hair dryer, as shown and described.
